Application October 16, 1945, Serial No. 622,533

9 Claims. (Cl. 101—116)

1

The present invention relates to duplicating apparatus and, more particularly, to manually operable mimeograph devices.

A general object of the present invention is the provision of a simple and efficient duplicating apparatus of economical construction which can readily be used in a simple manner effectively to produce manually mimeograph copies and which minimizes the expense attendant upon such production.

A more specific object of the invention is to provide such apparatus which in the making of mimeograph copies effectively utilizes a stencil-carrying cylinder which is rolled over a sheet of paper to be printed as it rests upon a relatively fixed base surface and which assures, in manual forward rolling of the cylinder during a printing, a setting up of certain conditions which will automatically and efficiently return the parts to their initial positions when the device is bodily lifted from the base surface and returned to its starting position for a repeat printing.

Another object of the invention is to provide a relatively stiff but flexible sheet having a smooth hard surface which may serve as an efficient cover for the stencil-carrying cylinder since it is of a protective character, which permits efficient employment in wrapping a cut stencil about the cylinder and constant observation of the stencil during such operation to assure proper placement of the stencil, and which may be used to economical advantage as a backing means for stencil sheet material during cutting of the latter thereby eliminating necessity for made up stencil assemblies each comprising a backing sheet that is torn off from the stencil sheet mount and thrown away subsequent to cutting, a common practice prior to the present invention.

A further object of the present invention is to provide such mimeograph apparatus which will permit efficient production of mimeographed copies with the printing accurately placed or positioned as desired on the successively printed copies even though they are produced by rolling a stencil-carrying cylinder manually over a base surface on which the printing paper is placed, the apparatus being characterized by guide means mounted thereon in a simple manner, which may be easily aligned with a reference mark on the base surface, and with means assuring that the other parts of the apparatus have assumed their initial positions as the printing cylinder is manually placed in starting position.

Still another object of the present invention is to provide such apparatus in which simple as-

2

sembly of parts effectively anchors in position the inking cloth and structural embodiments thereof which are readily constructed and allow efficient use and operation.

5 Other objects of the invention will in part be obvious and will in part appear hereinafter.

The invention accordingly comprises the features of construction, combination of elements and arrangement of parts, which will be exemplified in the construction hereinafter set forth and the scope of the invention will be indicated in the claims.

For a fuller understanding of the nature and objects of the invention, reference should be had to the following detailed description taken in connection with the accompanying drawings, in which:

Fig. 1 is an elevational section taken axially of an embodiment of the apparatus of the present invention, showing a protective cover in position;

Fig. 2 is a sectional view of the apparatus shown in Fig. 1, taken on line 2—2 thereof;

Fig. 3 is a sectional view similar to Fig. 2, but with the protective cover omitted for printing use of the apparatus, with parts broken away, showing only the portion of the printing cylinder adjacent the clamping plate and associated parts, together with guide means provided for assurance of efficient printing;

Fig. 4 is a front view, looking into the angle of the bent guide means of sheet material shown in mounted position in Fig. 3;

Fig. 5 is an enlarged detailed sectional view of the apparatus shown in Fig. 1, indicating the construction at the ends of the printing cylinder;

Fig. 6 is a perspective view on a smaller scale of the embodiment of the present invention shown in Figs. 1 to 5 inclusive, and illustrating its use in the production of mimeographed copies;

Fig. 7 is a perspective view of the printing cylinder with the clamping plate removed, and illustrating procedure of placement of a cut stencil thereon; and

Fig. 8 is a sectional view similar to Fig. 3 of a modified form of the apparatus of the present invention, but omitting the guide means.

In the drawings like numerals identify like parts throughout. The embodiment of the apparatus shown in Figs. 1 to 5 inclusive comprises a printing cylinder 10 preferably formed of perforated sheet metal or other relatively rigid material bent into cylindrical form. About the perforated sheet metal printing cylinder or drum 10 is wrapped an inking cloth 11 which is initially wider than the cylinder to provide marginal

edges 12, 12 with each turned inward about the adjacent end edge of the cylinder and into the latter. A pair of end members 13, 13 are provided each of which may comprise a disc having a circular portion or shoulder 14 to be received snugly within the end of the cylinder 10 and tightly to clamp therebetween the inwardly turned marginal portion 12 of the inking cloth 11. If desired, each end member or disc 13 may be of greater diameter than the inner diameter of the cylinder 10 and provided with the circular shoulder 14 by rabbeting so as to form an end flange 15 which will seat against the end of the cylinder with inking cloth interposed when the end member or disc is driven home to clamp the parts together. Such structural features make unnecessary provision of additional fastening means to secure the parts together, thereby assuring simplicity and economy of construction while providing for secure anchorage of the inking cloth in a desired stretched condition.

Further anchorage of the inking cloth 11 may be attained if desired by gluing the ends thereof to the cylinder 10 as it is wrapped around the latter, in a certain zone which, as indicated in Fig. 2, may extend an appreciable distance peripherally of the cylinder 10, say from a point 16 to a point 17, and completely across the cylinder in an axial direction.

The printing cylinder may be imperforate for some uses, in which case ink would be supplied to the inking cloth 11 from the outside. Preferably, however, the inking cylinder 10 is perforate and ink supplied to the inking cloth 11 from the interior of the cylinder. To assure even distribution of ink on the inner wall of the cylinder so that the inking cloth 11 will be supplied with ink from the interior of the cylinder through the perforations thereof throughout the effective surface of the inking cloth, a permeable layer of felt 18 is laid up against the inner wall of the cylinder and may be held or anchored in position in any suitable manner. Such anchorage of felt layer 18 may be accomplished in many ways as by having its end edges at 19, 19 abutting the inner faces of the end members or discs 13, 13. Split rings may be snapped into position interiorly of the felt layer to press it radially outward against the inner wall of cylinder 10. The ends of the layer of felt 18 alternatively may be anchored by an interior clamping plate 20 in the zone 16-17. In the latter zone an ink access hole 21, or a plurality thereof, if desired, is provided through the perforated cylinder 10 and any underlying structure, such as the layer of felt 18 and clamping plate 20. Such ink access hole or holes 21, of course, will also extend through the inking cloth 11 if a portion thereof extends to and beyond the location of such inking hole or holes. Introduction of a quantity of ink through the inking hole or holes 21 to the interior of the printing cylinder 10 will result in a thorough wetting of the felt layer 18 when the cylinder is oscillated or rotated. The ink saturating the felt layer 18 will then be fed through the perforations in the cylinder 10 to the inking cloth 11, the thickness of the perforated sheet metal of the cylinder and the character of the cloth and felt preferably being such as to assure physical contact through the perforations of the metal cylinder between portions of the inking cloth and the felt layer. As a result, efficient feed of ink from the interior of the cylinder to the inking cloth throughout the effective printing area of the latter is assured by means of capillary action.

For the purpose of clamping a cut stencil in position wrapped around the cylinder 10, an arcuate clamping plate 22 is provided which preferably covers the zone 16-17 of the printing cylinder. Releasable fastening means are provided for removably anchoring the clamping plate 22 to the cylinder 10. Such means may comprise a stud or bolt 23 extending through the cylinder wall in the zone 16-17 and anchored to the cylinder in any suitable manner, such as by being threaded into an internally threaded hole through the cylinder wall. The stud or bolt 23 may have a head 24 interiorly of the cylinder 10 between which and the inner wall of the cylinder 10 portions of the felt layer 18 and the interior plate 20 may be clamped, as proposed in Figs. 1 and 2; or, if desired, with omission of the interior plate, the head of the bolt may clamp portions of the felt layer against the inner wall of the cylinder, as suggested in Fig. 3. As indicated in Figs. 1, 2 and 3, the stud or bolt 23 extends outwardly from the cylinder 10 through a hole in the arcuate clamping plate 22 and threadably receives therebeyond a cap nut 25 adapted, when screwed down upon the stud, to clamp the parts together and, when removed, to permit removal of the clamping plate for mounting a cut stencil and guide, and/or a protective cover about the cylinder.

As shown in Figs. 1 and 2, the end members or discs 13, 13 are each provided with an axial hole through which is received a shaft 26 with the ends thereof 27, 27 extending beyond the end members or discs. Each end 27 of the shaft 26 is externally threaded and a manual knob or hand grasp 28 is screwed thereon. Each manual knob 28 is provided with a necked portion 29 which, when the apparatus is not in use, may rest in a notch or fork 30 on the end of an arm 31 supported upon a base 32 of a supporting stand.

The shaft 26 on the inside of the cylinder 10 has fixed thereto at 33 suitable spring means 34 tied or anchored to the cylinder 10 at 35. As shown in Figs. 1 and 2, such spring means 34 may comprise a helical spring disposed about the shaft 26 having one end received in a hole in the shaft at 33 and the other end 36 extending radially outwardly through one of the perforations in the cylinder 10, then laterally and back through another perforation in the cylinder, as shown at 35.

As a result of such tying of the shaft 26 and the cylinder 10 together by spring means, when the cylinder is placed upon a base surface the manual knobs 28, 28 firmly grasped and the shaft 26 bodily transported forward without rotation, the spring 34 will be wound up about the shaft 26 as the cylinder rolls over the base surface. Thus when the apparatus is then lifted from contact with the base surface, the spring 34 will unwind, rotating the printing cylinder 10 in the reverse direction to its initial position so that the apparatus may then be returned to its starting position on the base surface with the parts in their relative initial positions.

It will be understood that, to use the device in the making of mimeographed copies, a cut sheet of stencil paper is to be wrapped around the cylinder 10 overlying the inking cloth 11, and that the stencil will be held securely in position by having its ends clamped beneath the clamping plate 22. Accordingly, when the resultant assembly is rolled across the surface of a sheet of paper disposed upon a base surface, the paper will be printed in the usual manner of making mimeographed copies with, however, the relative motion

between the paper and the stencil being attained by movement of the cylinder supporting the stencil relative to the paper, which is held stationary, rather than by reverse operation of rotating the cylinder about a fixed axis and permitting the paper to move beneath it, as is common practice. Such procedure, however, will not assure proper orientation or placement of printing on the paper relative to the margins thereof.

Such proper orientation is assured in accordance with the present invention by the employment of suitable guide means. This guide means, as shown in Figs. 3 and 4 may comprise a piece of sheet material 37 which may be formed of relatively stiff cardboard or sheet plastic having one end portion 38 defined from another end portion 39 by a transversely extending bend or fold line 40, and with the two portions disposed relative to each other to form an acute angle therebetween. As shown in Fig. 3, after a cut stencil sheet 41 has been wrapped around the cylinder 10 with the inking cloth 11 lying therebeneath (and, of course, with the cap nut 25 and clamping plate 22 loosened or removed) the guide 37 will be placed with its portion 38 overlying the head end of the stencil 41 at 42. The clamping plate 22 will then be laid over the portion 38 of the guide 37 and the cap nut 25 screwed down to clamp the parts together. As a result, the portion 39 of the guide 37 will extend obliquely away from the cylinder 10 toward the fastening means or stud 23 and cap nut 25 assembly, as shown in Fig. 3. Although the guide 37 is preferably shaped as shown in Fig. 3 its portion 39 may be disposed with respect to portion 38 at other angles so long as it will readily flex, or bend along fold line 40, as to assume proper position when the apparatus is placed in its initial or starting position at time of use.

Since it is desired to employ the stud 23 and cap nut 25 or fastening means assembly as a guide for proper angular positioning of the apparatus relative to the base surface, such as by contact of the nearer portion at 43 of the cap nut with the base surface as the cylinder and stencil assembly are brought down to rest upon the base surface in starting position, the guide 37 has its portion 39 so shaped or constructed as to permit this action while assuring projection of the terminal edge 44 of the portion 39 beyond the fastening means as desired. For this purpose portion 39 of the guide 37 may be suitably cut away or apertured, and is preferably provided with a notch 45 in its terminal edge 44. Such notch or aperture will also provide ready access to the nut 25 for loosening, removing or tightening the same.

The apparatus desirably includes a protective cover 46 of suitable sheet material so as to avoid ink smears or smudges on objects accidentally brought into contact with the apparatus when not in use with or without the presence of a cut stencil. This protective cover 46 may be provided in a form which will permit its efficient employment in certain procedural steps preparing the apparatus for producing mimeographed copies and/or in the production of the latter. Such protective covering 46 may be a relatively stiff but flexible sheet of suitable material such as transparent, translucent or opaque plastic. It preferably comprises a transparent sheet of suitable material, such as a flexible sheet of transparent plastic having a fair degree of stiffness and a relatively smooth hard surface. The useful protective characteristic of the cover-

ing sheet 46 is illustrated in Figs. 1 and 2, wherein it is indicated that the transparent plastic sheet is wrapped about the cylinder 10 and its overlying elements, such as the inking cloth 11 and a cut stencil 41. The ends of the protective sheet 46 are clamped in position beneath clamping plate 22. This protective cover 46 also enhances the appearance of the idle apparatus.

Another useful feature of the protective sheet

10 46 is illustrated in Fig. 7, wherein it is indicated that the cut stencil sheet 41 may be efficiently applied to the exterior of the printing cylinder 10 with the aid of the transparent sheet 46. This procedure is accomplished in the following manner: The cap nut 25 and clamping plate 22 are removed. Precaution is taken to assure a sufficient quantity of ink within the printing cylinder. A cut stencil sheet 41 is then positioned with its end edge at the head properly located in the zone

20 16-17. For this purpose the device may be provided with a suitable guide mark with which the end edge at the head of the cut stencil 41 may be aligned. Such guide mark may be provided by 25 an end edge of the inking cloth 11 or by a suitable mark on the end portion thereof or upon any overlying element.

The flexible transparent, relatively stiff sheet

46 is then employed to wrap the cut stencil 41 30 about the cylinder 10. This may be accomplished either by having the cut stencil lying against the undersurface of the transparent sheet 46 at the time the cut stencil has its end edge at the head aligned with the index mark on the cylinder, 35 or the transparent sheet 46 may be brought down upon the stencil sheet 41 after the latter has had its head end properly placed on the cylinder. The two sheets comprising the stencil 41 and the transparent sheet 46 are then wrapped about the cylinder 10. The transparency of sheet 46 permits continual observation of the underlying stencil sheet 41 during the wrapping of the latter about the cylinder so that one can make certain that the stencil is properly stretched and 45 smoothed about cylinder 10 and that the ink starts evenly through the cut places in the stencil.

After so wrapping the cut stencil 41 about the cylinder 10, the ink in the inking cloth 11 will assure that it will be held in its smoothed condition while the transparent sheet 46 is being replaced by the guide 37 and clamping plate 22, and the cap nut 25 is being screwed down securely. Of course, this procedure will smear the undersurface of the transparent sheet with ink. These smears can, however, readily be removed by wiping or other simple cleansing action, due to the nature of the material from which the transparent sheet is made.

This simplified procedure in mounting the sten-

60 cil sheet 41 eliminates the necessity for having the stencil sheet fastened to a heading strip provided with eyelets adapted to be engaged over hooks or studs, as is common practice. Further, it permits the employment of unbacked stencil 65 sheets precut and stacked or cut from a roll of stencil sheet material at time of use, as contrasted with the usual practice of using stencil sheets which, in addition to having an apertured heading strip, are provided with a tear-off relatively stiff paper backing sheet. This economy in materials and procedure, of course, however, will require the provision of some sort of backing sheet to be used in the cutting of the stencils. As indicated below, this necessity may be answered 70 by the transparent sheet 46, which, as previously

pointed out, will also serve both as a protective cover and as an aid in the wrapping of a cut stencil 41 into position on the cylinder 10 in the following manner.

The transparent flexible, relatively stiff sheet 46 may also serve as a backing sheet in the cutting of stencils. A piece of stencil paper 41 may be cut from a roll thereof. This may then be placed upon the transparent sheet 46. The two together may then be rolled into a typewriter and the stencil sheet 41 cut with the desired message while using the transparent sheet 46 next to the platen as a protective backing sheet. Upon removal of the cut stencil 41 with the transparent sheet 46 from the typewriter, the two may be placed upon the cylinder 10 in the manner indicated above, with the transparent sheet being employed properly to wrap and smooth the cut stencil about the cylinder. Of course, the transparent sheet 46 may also serve as a suitable backing sheet in cutting a stencil with a manual tool to provide designs thereon. The relative stiffness of the transparent sheet 46 permits it to lie flat for this purpose when it is not being bent around in the wrapping of a cut stencil about the cylinder or wrapped around the latter as a protective cover therefor.

It will thus be seen that the protective sheet 46 should have certain characteristics. It should be transparent to permit observation therethrough. It should be relatively stiff so that it will lie flat when unflexed. It should be of such character as to have a smooth, hard surface and be relatively impervious to liquids so as to provide an ideal backing for the cutting of stencils and to provide for ready removal of ink smears therefrom. And further, it should be flexible to permit its employment as an aid in the wrapping of a cut stencil about the cylinder or as a protective cover for the printing cylinder. A relatively thick sheet of transparent plastic, such as cellulose acetate, Cellophane or other well known plastic sheet materials, will satisfy these requirements.

In operation of the apparatus a primary base surface, such as a table top with an overlying cover or sheet on which marks may be made, as diagrammatically indicated at 47 in Fig. 6, is selected. The operator will place thereon reference marks, such as those indicated at 48, 49, to which are to be aligned the terminal edge 44 of portion 39 of the guide 37. The duplicating apparatus is set up with a cut stencil 41 wrapped about the cylinder 10 and the guide 37 clamped in proper position, all in the manner as proposed above. The apparatus is then bodily moved to the base surface 47 with the hands of the operator grasping the manual knobs 29, 28, and the cylinder is placed upon the base surface with the terminal edge 44 of the guide 37 aligned with the marks 48, 49 and also with the portion 43 of the clamping cap nut 25 resting upon the base surface. The operator then transports the shaft 26 and its knobs 28, 29 forward without rotation to cause the printing cylinder 10 to roll across the base surface 47. This will cause a printing of the indicia cut in the stencil down upon the base surface 47.

The operator then places or arranges a blank sheet of paper 49 upon the base surface 47 in a manner so that the printing will be arranged or oriented as desired with respect to the marginal edges of the piece of paper. The operator places reference marks upon the base surface 47, such as those at 50, 51, to guide him in proper

placement of the succeeding sheets of paper to be printed.

The duplicating apparatus is then positioned as described above, with the terminal edge 44 of guide 37 aligned with the marks 48, 49, and with the cap nut 25 resting against the base surface 47 at 43. Thereafter, the operator rolls the printing cylinder forward in the manner indicated above so that the sheet of paper 49 will be printed in the desired manner with the printing properly oriented thereon. The operator then bodily picks up the duplicating apparatus, substitutes an unprinted sheet for the printed sheet at 49 with its corners aligned with the marks 50, 51 and then repeats the operation for printing of the next succeeding sheets to be mimeographed.

It will thus be seen that the guide lines or marks 50, 51 properly dictate placement of the sheets of paper 49 so that the printing will be properly oriented thereon, that the guide lines or index marks 48, 49 will properly dictate placement of the printing cylinder so that the printing on the sheet will begin at the head end where desired, and that contact of the fastening-means or the cap nut 25 with the base surface 47 at 43 will assure, in cooperation with the guide 37 when its edge 44 is aligned with the marks 48, 49, the proper placement at the starting position of the apparatus relative to the paper to be printed. As indicated above, the return spring 34 assures that the printing cylinder will be rotated in a reverse direction after having been rolled forward during printing so as to permit the guide 37 and fastening means or cap nut 25 to be located in their initial positions.

As shown in Fig. 8, an embodiment of the invention may comprise a perforated cylinder 10 around which is wrapped the inking cloth 11 which may be secured thereto in the manner indicated above, such as by having inwardly turned edges thereof clamped between the inner wall of the cylinder and the end members 13, 13. The ends of the inking cloth 11 may be employed to render imperforate or close the apertures in the zone 16-17 of the perforated cylinder 10. This may be accomplished by gluing those ends to the cylinder 10 in that zone. In such case the ink access hole 21 will be formed through a portion of the inking cloth. The latter may be further anchored in position by an inner plate 51 which may have a threaded hole therein into which the stud 23 is screwed so as tightly to clamp the ends of the inking cloth 11 to the outer surface of the cylinder 10. In the case of the employment of the inner clamping plate 51 a hole 52 will be formed therein aligned with the ink access hole 21. Such inner clamping plate 51 may supplement the gluing to render the zone 16-17 imperforate except for the ink access hole 21, or it may be employed in substitution for the gluing.

The ink access hole may be closed by lapping over it the end 53 of the cut stencil 41 and holding the latter tightly down against the inner plate 51 by means of the clamping plate 22. This will prevent spilling out of any excess ink in the printing cylinder.

As indicated above, any suitable reference means in the zone 16-17 of the printing cylinder 10 may be employed for dictating the proper location of the edge of the stencil sheet 41 at its head end when being wrapped around and mounted on the printing cylinder 10. For this purpose, in the embodiment shown in Fig. 8 the inner plate 51

may be provided at 54 with a suitable scratch or mark at which the head end of the cut stencil 41 is to be positioned. Of course, it will be understood that with reference to the embodiment shown in Fig. 8 it is intended that a suitable guide means, such as that shown at 37 in Figs. 3 and 4, may be employed to advantage and in a similar manner. As proposed in Fig. 8, the apparatus may, if desired, be employed without the use of the inner layer of felt 18. It will be understood, however, that if desired such an ink spreading felt layer 18 may be employed within the cylinder 10 of the embodiment shown in Fig. 8.

It will thus be seen that the objects set forth above and those made apparent from the above description are efficiently attained, and since certain changes may be made in the above construction and different embodiments of the invention could be made without departing from the scope thereof, it is intended that all matter contained in the above description or shown in the accompanying drawings shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described my invention, what I claim as new and desire to secure by Letters Patent is:

1. A duplicating apparatus comprising, in combination, a printing cylinder of sheet material, an inking cloth wrapped therearound and anchored thereto in the vicinity of a certain zone with the cloth being initially wider than said cylinder, a pair of end members each having a circular portion received snugly within an end of said cylinder with an edge of said inking cloth turned inward about the end edge of said cylinder into the latter and clamped tightly between said circular portion of said end member and the inner surface of said cylinder, a shaft rotatably received through said end members and carrying beyond the latter means to permit manual transport thereof without rotation, spring means tying said cylinder to said shaft to be wound up as said cylinder is rolled forward over a base surface by said shaft without rotation of the latter for return of the cylinder to its angular starting position when the device is lifted bodily from the base surface, a clamping plate overlying that zone adapted to clamp a stencil sheet in position about said cylinder, and printing guide means comprising a bent piece of sheet material having one end portion clamped beneath said clamping plate and the other end portion extending away from said cylinder and terminating in an edge adapted to be aligned with reference means on the base surface for proper location of printing on paper prearranged on the base surface with respect to the reference means.

2. A duplicating apparatus comprising, in combination, a printing cylinder of sheet material, an inking cloth wrapped therearound and anchored thereto in the vicinity of a certain zone with the cloth being initially wider than said cylinder, a pair of end members each having a circular portion received snugly within an end of said cylinder with an edge of said inking cloth turned inward about the end edge of said cylinder into the latter and clamped tightly between said circular portion of said end member and the inner surface of said cylinder, a shaft rotatably received through said end members and carrying beyond the latter means to permit manual trans-

ual transport thereof without rotation, spring means tying said cylinder to said shaft to be wound up as said cylinder is rolled forward over a base surface by said shaft without rotation of the latter for return of the cylinder to its angular starting position when the device is lifted bodily from the base surface, a clamping plate overlying that zone adapted to clamp a stencil sheet in position about said cylinder, and printing guide means comprising a bent piece of sheet material having one end portion clamped beneath said clamping plate and the other end portion extending back over a portion of said clamping plate to extend obliquely away from said cylinder and terminating in an edge adapted to be aligned with reference means on the base surface for proper location of printing on paper prearranged on the base surface with respect to the reference means.

3. A duplicating apparatus comprising, in combination, a printing cylinder of perforate sheet material, an inking cloth wrapped therearound and anchored thereto in the vicinity of a certain zone with the cloth being initially wider than said cylinder, a pair of end members each having a circular portion received snugly within an end of said cylinder with an edge of said inking cloth turned inward about the end edge of said cylinder into the latter and clamped tightly between said circular portion of said end member and the inner surface of said cylinder, a shaft rotatably received through said end members and carrying beyond the latter means to permit manual transport thereof without rotation, spring means tying said cylinder to said shaft to be wound up as said cylinder is rolled forward over a base surface by said shaft without rotation of the latter for return of the cylinder to its angular starting position when the device is lifted bodily from the base surface, the resultant cylindrical structure having in the mentioned zone an ink access hole extending therethrough to the interior of said cylinder, a clamping plate overlying that zone adapted to clamp a stencil sheet in position about said cylinder and to cover the ink access hole, releasable means in said zone projecting beyond said clamping plate and biasing the latter toward said cylinder, and printing guide means comprising a bent piece of sheet material having one end portion clamped beneath said clamping plate and the other end portion extending back over a portion of said clamping plate to extend obliquely away from said cylinder with portions of its terminal edge extending beyond said releasable means.

4. A duplicating apparatus comprising, in combination, a printing cylinder of perforate sheet material, an inking cloth wrapped therearound and anchored thereto in the vicinity of a certain zone with the cloth being initially wider than said cylinder, a pair of end members each having a circular portion received snugly within an end of said cylinder with an edge of said inking cloth turned inward about the end edge of said cylinder into the latter and clamped tightly between said circular portion of said end member and the inner surface of said cylinder, a shaft rotatably received through said end members and carrying beyond the latter means to permit manual transport thereof without rotation, spring means tying said cylinder to said shaft to be wound up as said cylinder is rolled forward over a base surface by said shaft without rotation of the latter for return of the cylinder to its angular starting position when the device is lifted bodily from the

11

base surface, the resultant cylindrical structure having in the mentioned zone an ink access hole extending therethrough to the interior of said cylinder, a clamping plate overlying that zone adapted to clamp a stencil sheet in position about said cylinder and to cover the ink access hole, releasable means in said zone biasing said clamping plate toward said cylinder and projecting beyond said plate to serve as a limiting guide for rotational movement of said cylinder over the base surface, and printing guide means comprising a bent piece of sheet material having one end portion clamped beneath said clamping plate and the other end portion extending back over a portion of said clamping plate to extend obliquely away from said cylinder with portions of its terminal edge extending beyond said releasable means, said obliquely extending portion of said guide means being so shaped as to permit said projecting releasable means to contact the base surface when the cylinder is placed for printing a sheet of paper on the base surface with the terminal edge of said guide means aligned with reference means on the base surface.

5. In a duplicating apparatus, the combination comprising, a printing cylinder adapted to carry a stencil sheet wrapped therearound and successively to print sheets of paper on a base surface when said cylinder is rolled thereover, a releasable clamping plate extending across said cylinder to hold the ends of the stencil sheet in position, and printing guide means comprising a piece of sheet material having one end portion clamped beneath said clamping plate and the other end portion extending away from said cylinder and terminating in an edge adapted to be aligned with reference means on the base surface for proper location of printing on paper prearranged on the base surface with respect to the reference means.

6. In a duplicating apparatus, the combination comprising, a printing cylinder adapted to carry a stencil sheet wrapped therearound and successively to print sheets of paper on a base surface when said cylinder is rolled thereover, a releasable clamping plate extending across said cylinder to hold the ends of the stencil sheet in position, and printing guide means comprising a bent piece of sheet material having one end portion clamped beneath said clamping plate and the other end portion extending back over a portion of said clamping plate to extend obliquely away from said cylinder and terminating in an edge adapted to be aligned with reference means on the base surface for proper location of printing on paper prearranged on the base surface with respect to the reference means.

7. In a duplicating apparatus, the combination comprising, a printing cylinder adapted to carry a stencil sheet wrapped therearound and successively to print sheets of paper on a base surface when said cylinder is rolled thereover, a releasable clamping plate extending across said cylinder to hold the ends of the stencil sheet in position, releasable means projecting beyond said clamping plate and biasing the latter toward said cylinder, and printing guide means comprising a bent piece of sheet material having one end portion clamped beneath said clamping plate and

12

the other end portion extending back over a portion of said clamping plate to extend obliquely away from said cylinder with portions of its terminal edge extending beyond said releasable means.

5 means.

8. In a duplicating apparatus, the combination comprising, a printing cylinder adapted to carry a stencil sheet wrapped therearound and successively to print sheets of paper on a base surface
10 when said cylinder is rolled thereover, a releasable clamping plate extending across said cylinder to hold the ends of the stencil sheet in position, releasable means biasing said clamping plate toward said cylinder and projecting beyond said
15 plate to serve as a limiting guide for rotational movement of said cylinder over the base surface, and printing guide means comprising a bent piece of sheet material having one end portion clamped beneath said clamping plate and the other end portion extending back over a portion of said
20 clamping plate to extend obliquely away from said cylinder with portions of its terminal edge extending beyond said releasable means, said obliquely extending portion of said guide means being so shaped as to permit said projecting releasable means to contact the base surface when the cylinder is placed for printing a sheet of
25 paper on the base surface with the terminal edge of said guide means aligned with reference means on the base surface.

30 9. In a duplicating apparatus, the combination comprising, a printing cylinder adapted to carry a stencil sheet wrapped therearound and successively to print sheets of paper on a base surface when said cylinder is rolled thereover, a releasable clamping plate extending across said cylinder to hold the ends of the stencil sheet in position, a threaded stud anchored to said cylinder and extending up through a hole in said clamping plate, a nut threaded on said stud and extending beyond said clamping plate while biasing the latter toward said cylinder, and a printing guide consisting of a bent piece of sheet material having one end portion clamped beneath an edge of said clamping plate and the other end portion extending back over a portion of said plate and obliquely away from said cylinder and beyond said stud and nut assembly, the terminal edge of said obliquely extending portion being notched to permit said stud and nut assembly to contact the base surface when the cylinder is placed for printing a sheet of paper on the base surface with the terminal edge aligned with reference means on the base surface.
